(57) **CLAIM**

The ornamental design for a bed caddy, as shown and described.

DESCRIPTION

FIG. 1 is a top front side perspective view of a bed caddy showing my new design;

FIG. 2 is a front view of the bed caddy;

FIG. 3 is a rear view of the bed caddy;

FIG. 4 is a top view of the bed caddy;

FIG. 5 is a bottom view of the bed caddy;

FIG. 6 is a right side view of the bed caddy;

FIG. 7 is a left side view of the bed caddy; and,

FIG. 8 is a top front side perspective view of the bed caddy with a band in an alternate position.

The broken lines in the drawing figures are illustrative of portions of the article forming no part of the claimed design.
